UNITED STATES PATENT OFFICE.

A. HAMMOND, OF JACKSONVILLE, ILLINOIS.

IMPROVEMENT IN MOLE-PLOWS.

Specification forming part of Letters Patent No. 27,796, dated April 10, 1860.

To all whom it may concern:

Be it known that I, A. HAMMOND, of Jacksonville, in the county of Morgan and State of Illinois, have invented a new and useful Improvement in Mole-Plows; and I do hereby declare that the following is a full, clear, and exact description thereof, reference being had to the accompanying drawings, forming a part of this specification, in which—

Figure 1 represents a side view of my improved machine, with the tooth or shoe for forming the drain sunk into the ground. Fig. 2 is a plan view of Fig. 1.

Similar letters of reference indicate corresponding parts in both figures.

This invention relates to improvements in that class of ditching-machines known as the "mole-plow." It is used to drain off swamp and low land. The drains are formed by cutting channels in the ground from one to two or more feet in depth, all leading to one common conduit or channel. In using these mole-plows it is frequently necessary to draw the shoe out of the ground, and as it may be sunk pretty deep in wet and tough boggy mud it is found to be a very difficult operation. The object of this invention is to construct the machine in such a way that the standard for carrying the tooth or shoe may be adjusted longitudinally with the beam of the machine. This adjustment given to the standard will be useful for regulating the direction of the point of the shoe for forming the drain without the necessity of drawing the shoe out of the earth to set it, all as will be hereinafter described.

To enable those skilled in the art to fully understand my invention, I will proceed to describe its construction and operation.

In the drawings, A represents a beam of the usual length and strength, mounted upon wheels or rollers B B and a rear roller, C. These wheels allow the machine to roll over the surface of the ground without sinking into it; they also steady the beam A during the operation of ditching.

Near the rear end of the beam and passing through the same is an adjustable standard, D, with its front edge beveled to a knife-edge for the purpose of cutting freely through sods,

&c., as the machine is drawn forward. This standard carries on its lower end my patented shoe, which is fully described in my former specification. This shoe is raised or depressed in the ground by a winch and endless worm-screw E, which latter operates a large spurred wheel, F, on the shaft of which is a pinion, F', which engages with rack-teeth on the back of the standard D. On the opposite side of the standard to pinion F is a friction-roller, G, against which the standard acts while it is being raised or depressed by the pinion F'. A friction-bearing, G', Fig. 1, placed in a shoe-box, H, serves to relieve the standard of friction at this point. By the use of those friction-wheels the standard can be raised or depressed with great ease, while without them the operation would be found very difficult and impracticable with ordinary power. The gearing and friction-wheel G, forming the upper bearing for the standard D, have their bearings in a sliding plate, J, which rests upon a plate, K, with lugs *a a* projecting up from it for keeping the movable plate down on the plate K.

L is a screw-shaft, one end of which is tapped into the vertical lip *b* of the fixed plate K, while the other end passes beyond the front end of the beam A, and is provided with a winch, *c*.

Now, it will be seen, from this description of the parts constituting my invention that the top of the standard D can be moved or vibrated in a direction with the length of the beam A, that it can be set at any desirable angle with the beam, and that it can be brought to a vertical position by the use of the screw-shaft L while in the ground. This is done by loosening the screw-shaft L and moving the machine forward. This screw, with the movable plate J, carrying the upper end of the standard, can be used also for adjusting the position of the standard and also of the shoe while the same are in the ground, so as to regulate the depth of the hole to be formed below the surface of the ground. For instance, by inclining the standard the shoe will have an upward tendency, and may thus be elevated or entirely drawn out of the ground. After being elevated sufficiently the standard may be brought to a vertical position again. The hole cut through

the beam A for the reception of the standard D is sufficiently elongated to allow for any desired adjustment of the standard, as described.

Having thus described my invention, what I claim, and desire to secure by Letters Patent, is—

The combination, with the standard D, of the movable plate J, adjusting set-screw L, and

friction-rollers G G, arranged as set forth, so as to regulate the depth for forming the drain, and at the same time to facilitate the removal of the shoe from the ground.

A. HAMMOND.
